HOLDER

William F. C. Brooker, Paramus, N. J., assignor to
 Enoch Morgan's Sons Co., New York, N. Y., a
 corporation of New York

Application May 3, 1933. Serial No. 669,093

3 Claims. (Cl. 221—61)

This invention relates to holders and has for an object to provide for commercial packages of cleaning powder or the like a rigid holder which retains and conceals such package while permitting the contents thereof to be discharged in the usual manner. Such a holder may be in the form of a metal casing open at one end to permit the insertion of the package, the casing being of proper shape and size to have a friction fit with the package, thereby holding the same securely. The top of the casing is provided with one or more recesses leading to the edge of the casing and cooperating with the top of a package contained in the casing to form channels providing guideways for delivering the contents of the package to any desired point. The contents of the package may be discharged in the customary manner merely by lifting and tilting the casing and the contained package to cause the contents of the package to flow out through apertures provided in the package top for that purpose. The casing protects the package against distortion by handling and obviates the unsightly appearance of a damaged or crushed package as well as affords a more sightly and pleasing appearance than afforded by the usual commercial package.

Furthermore, the casing may be colored or otherwise ornamented so that it will harmonize in color and appearance with the fixtures and decorations of the kitchen, bath-room or other room in which the package is kept.

Other objects, novel features and advantages of this invention will be apparent from the following specification and accompanying drawing, wherein:

Fig. 1 is a perspective view of an embodiment of the invention;

Fig. 2 is a side elevation thereof partially broken away, and

Fig. 3 is a section on the line 3—3 of Fig. 2.

The holder 10 comprises a casing open at its bottom end and having the top 11 closing the upper end. The casing is rectangular in cross-section as clearly shown in Fig. 3 and the side walls of the casing have smooth plane surfaces. The top 11 is cut away to form recesses 12 leading to opposite edges of the top. A rib 13 may be provided on the top and having the same general configuration as the cross-section of the casing.

In use, the casing 10 fits over and encloses a commercial package of cleansing powder or the like, such package comprising a container 15 of cardboard or other similar material within which

the powder is arranged. The package 15 is introduced into the casing 10 through the open bottom end thereof and the size and shape of the interior of the casing bears such relation to the size and shape of the package 15 that there is a friction fit between the casing and the package. The package is thus securely retained within the casing and the two constitute a single unit. Preferably, the casing 10 is of such height that the package 15 is not quite completely received within the casing but a short portion thereof is exposed. Thus, when the unit comprising the package and casing are moved along a surface, the casing is out of contact with the surface and cannot damage such surface.

The top of the package 15 contacts with the inner face of the top 11 and the recesses 12 form with the top of the package discharge channels through which the contents of the package may be directed to any desired spot. The top of the package 15 is punched in as at 16 to provide discharge openings communicating with the delivery channels above referred to. Preferably, the package 15 is provided in its top with weakened spots which are suitably indicated as the spots to be punched to form the discharge openings 16.

The sides of the casing 10 are continuous and remain in fixed relationship to each other. The package 15 is relatively yieldable so that although its outside dimensions are substantially the same as the inside dimensions of the casing 10, the package can be introduced into the casing. The yielding of the package results in the friction fit by which the package is securely retained in the casing. After the contents of a package have been fully discharged, the container 15 is withdrawn from the casing 10 and a full package substituted in its place.

The container may be fabricated by a die molding operation or it may be fabricated from sheet metal bent into the proper shape and size. The casing may be painted or otherwise ornamented to give it a pleasing and attractive appearance. Such a casing protects the package while permitting its contents to be as accessible as without the casing. The casing and package being in effect a unit makes possible the discharge of the contents in the same manner as if the package were not assembled with the casing. All the advantages of the package are retained and the advantages of protection and improved appearance are added.

It is of course understood that various modifications may be made in the structure of the de-

vice above described, without in any way departing from the spirit of the invention as defined in the appended claims.

I claim:

- 5 1. A holder for a package of cleaning powder or the like comprising a rigid casing of substantially the same interior cross-sectional dimensions as the exterior cross-sectional dimensions as the package, said package being yieldable whereby a friction fit exists between said casing and package, and recesses in the top of the casing leading to the edges thereof and being adapted to cooperate with the top of a package in the casing to form delivery channels.
- 10 2. A holder for a package of cleaning powder or the like, said package being rectangular in cross-section and being yieldable and said holder comprising a casing rectangular in cross-section and of substantially the same interior cross-sectional dimensions as the exterior cross-sectional dimensions of said package, the sides of said casing having continuous plane surfaces, the
- 15 20

yieldability of said package effecting a friction fit between said casing and package, and recesses in the top of said casing leading to the sides thereof and adapted to cooperate with the top of the package in the casing to form delivery channels.

3. A holder for a package of cleaning powder or the like, said package being rectangular in cross-section and being yieldable and said holder comprising a casing rectangular in cross-section and of substantially the same interior cross-sectional dimensions as the exterior cross-sectional dimensions of said package, the sides of said casing having continuous plane surfaces, the yieldability of said package effecting a friction fit between said casing and package, and recesses in the top of said casing leading to the sides thereof and adapted to cooperate with the top of a package in the casing to form delivery channels, said casing being of less height than said package to expose a portion thereof.
